RAILWAY TRUCK STRUCTURE AND
METHOD OF ASSEMBLING AND DIS-
ASSEMBLING THE SAMEJames C. Travilla, Jr., Swarthmore, Pa., assignor
to General Steel Castings Corporation, Granite
City, Ill., a corporation of Delaware

Application April 26, 1944, Serial No. 532,710

12 Claims. (Cl. 105—190)

1

The invention relates to railway rolling stock, and more particularly to railway trucks of the type in which the load-supporting bolster is supported on springs positioned near the opposite ends of the bolster and the loads on the springs are equalized by levers extending across the truck so as to stabilize the vertical movements of the opposite ends of the bolster, as disclosed in J. C. Travilla, Jr., and E. C. Jackson Patent 2,284,695, issued June 2, 1942. The present invention relates to the construction of such stabilizing levers and associated parts and the method of assembling and disassembling them.

The main object of the invention is to facilitate the assembly and disassembly of the parts, and this object is attained by arranging the parts and their assembly so that the bolster springs can be compressed independently of the stabilizing lever and the elements supporting the same, whereby the lever and elements may be relieved of their load and manipulated independently of the springs.

This general object and other detail objects as will appear from the following description are attained by the structure illustrated in the accompanying drawings, in which—

Figure 1 is a top view of a truck of the type referred to. Parts of the structure are broken away to permit the drawing to be made to a larger scale.

Figure 2 is in part a side elevation and in part a longitudinal vertical section taken on the line 2—2 of Figure 1.

Figure 3 is a transverse vertical section taken on the line 3—3 of Figure 1.

Figure 4 is a detail top view of one end of one of the stabilizing levers.

Figure 5 is a detail vertical section taken on the line 5—5 of Figure 4 and showing associated parts.

Figure 6 is a diagrammatic view corresponding generally to Figure 3 but showing the parts in the position assumed during the operation of applying or removing a bolster spring or stabilizing lever to or from the other truck parts.

Figure 7 is a similar diagrammatic view illustrating a different operation of applying or removing a bolster spring and stabilizing lever.

Figure 8 is a diagrammatic view illustrating another operation of applying, or removing, the bolster springs and stabilizing levers to or from the bolster while the bolster is disassembled from the other truck parts.

Figure 9 is a diagrammatic view looking at right angles to Figure 8.

2

The truck includes spaced axles 1 with wheels 2; journal boxes 3 carrying equalizers 4 on which are mounted the truck springs 5 which carry the truck frame 6. Preferably, the truck is of the lateral-motion bolster type and has pairs of swing hangers 7 and 17 pivotally suspended from the frame by pins P at opposite sides of the truck, the hangers carrying cross bars 9 and 19 respectively. The bolster 8 extends transversely of the truck over cross bars 9 and 19 and below frame wheel pieces 6b. Stabilizing levers 10 and 20 are arranged substantially end to end transversely of the truck and they are fulcrumed intermediate their ends to the bolster by pins or tie rods 11 and 21 respectively. The inner ends of levers 10 and 20 are interconnected by links 12 and bolts 13, 23. The outer end of each lever is forked to provide a recess 18 and the underside of the lever at each side of recess 18 is grooved at R to rest upon one of the corresponding cross bars 9, 19. A seat member 14, 24 is mounted upon the outer end of each lever 10, 20 and forms a seat for one or more bolster-supporting springs 15 and 25 respectively. Preferably, rubber blocks K, each having steel top and bottom plates, to which the rubber is vulcanized, are interposed between the lever and the spring seat. These blocks accommodate the relative tilting of the spring seat and the lever. However, if desired, the spring seat 30 may rest directly on the end of the lever, and the parts may be provided with concavo-convex interengaging surfaces as shown in Figure 8 of Travilla and Jackson Patent 2,284,695, issued June 2, 1942.

The vehicle body B is supported mainly on the bolster center plate 16 but body B and bolster 8 are provided with cooperating side bearings S and S' respectively to take a portion of the body load when the body tilts. The upwardly facing 40 truck side bearings S' are immediately above the corresponding downwardly facing portion of the bolster forming seats for bolster supporting springs 15 and 25. The vehicle body, the bolster, its supporting springs and the stabilizing levers 45 may swing laterally as a unit on hangers 7, 17. If the vehicle is standing on level track, levers 10, 20 do not function except as they form a filler between the spring seats and the cross bars, but any tendency of the bolster to tilt vertically, due to the presence of forces which might act unequally on the bolster springs is prevented by the levers. Any force tending to raise or lower the outer end of either lever will be distributed equally to both springs by the levers, and this tends to 50 stabilize the relation between the bolster and the 55

swing hangers and improve the riding qualities of the truck, as described in the above-mentioned patent.

Heretofore it has been difficult to assemble and disassemble the bolster and its springs with the cross stabilizers and the swing hangers because in the assembly the springs are under compression and the holes for the fulcruming pins 11, 21 and, likely, connection pins 13, 23 must be forced into alignment to accommodate the insertion and removal of the pins.

In the present construction, the outer end of each lever 10, 20 is provided with a central recess or passage 18, and each spring seat 14, 24 spans the space between the forked ends of the lever and is provided with a depending boss 14a, 24a which may be projected through recess 18. This makes it possible to compress springs 15, 25 without pressure on the levers 10, 20 and their pins 11, 13, 21 and 23.

The assembling and disassembling of the parts may be performed in various ways, some of which will be described below as illustrative. For example, if the truck is completed, as shown in Figures 1-3, and it is desired to remove levers 10, 20 or springs 15, 25, pin 23 may be withdrawn first (since there is no load on this pin when the parts are in their normal position), then jacks 30 (Figure 6) may be placed under the body bolster or the car side sills or the car end sill and may be raised (the truck and body bolsters being held together by the center pin C) until the top of the truck bolster 8 engages the underside of the truck frame wheel pieces 6b. Then a jack 31 may be placed under one of the levers, 20 for example, and raised, compressing the adjacent spring 25 so as to take the load off of cross bar 19, which may be swung outwardly to clear the end of lever 20, and removed and a block 32 applied to the projection 24a depending from spring seat 24, the upper portion of the block extending through the recess 18 in the lever. Then jack 31 may be lowered until lever 20 is relieved of its load, whereupon pin 21 may be readily removed and the lever detached from the bolster. Jacks 30 may be raised further to permit spring 25 to expand to its free height, whereupon it may be removed. (Another extended jack could be used in place of block 32, and the lowering of such jack would render it unnecessary to further elevate jacks 30 as described.) Cross bar 9, lever 10 and spring 15 may be removed similarly. All the parts may be reassembled by reversing the order of the steps described above.

Another operation for removing the levers and bolster springs may follow the initial steps described above but without first removing pin 23. After the bolster is supported from the center pin and jack 31 has relieved cross bar 19 of its load, the cross bar is swung out from under lever 20, and jack 31 may be lowered, but the downward movement of lever 20 under the thrust of spring 25 will be limited by the connection of the inner end of the lever to lever 10 and the support of the outer end of the latter by cross bar 9. Hence jack 31 may be disengaged from lever 20 and may be shifted to the position in which block 32 is indicated where it may project through the recess 18 in the end of lever 20 and may be elevated to relieve lever 20 of the pressure of bolster spring 25, whereupon pins 21 and 23 may be readily removed and lever 20 dropped from the assembly. Thereafter lever 10 may be removed by use of jack 31 and block 32 as described in the preceding paragraph. Obviously, lever 10 may

be first removed, independently of lever 20, in the same manner lever 20 is removed as described herein. The operation or operations may be reversed for assembling the springs and levers with the bolster.

If a plurality of jacks are not available to operate as described above, it is possible to disassemble and reassemble the parts by use of a single jack (see Figure 7). The single jack 33 may be placed under lever 20 and elevated until the bolster has been lifted an amount exceeding the distance between the free height and the load height of the bolster springs. (During this movement, the bolster will have engaged the underside of the frame wheel pieces and the parts will be in the relative positions shown.) Then the car body may be supported by blocks L under the adjacent end sill or side sills similar to the supports afforded by jacks 30 (Figure 6) and a block 34 placed between the inner end of lever 10 and rib 8a on the bolster. This block will keep the bolster springs compressed to their normal loaded height irrespective of jack 33. Then jack 33 may be lowered and both cross bars 9 and 19 will be relieved of their load and bar 19 may be swung outwardly to clear the outer ends of lever 20 and may be removed or the entire swing hanger assembly may be detached by removing the associated swing hanger pins P. Then the jack may be shifted to the position indicated in broken lines at 33a where it projects through the recess 18 in the end of lever 20 and may be extended to relieve the lever of the pressure of bolster spring 25, whereupon pins 21 and 23 may be readily removed and lever 20 dropped from the assembly.

Then the jack may be lowered, thus allowing spring 25 to expand to its free height when it may be removed. The other bolster spring 15 remains compressed due to block 34. After removing bar 9, which is free of load as explained above, the jack may be placed under the seat of spring 15 and raised to take the pressure of the spring off of lever 10 when its fulcrum pin 11 may be removed and the lever and block 34 may be dropped. Then the jack may be lowered until spring 15 is expanded to its free length when the jack and the spring may be removed. The parts may be assembled in like manner but with the operations in reverse order.

If the truck is to be assembled, or disassembled, independently of the car body as, for example, in the plant where the truck is manufactured, or in a car repair shop or other place with suitable equipment, as referred to below, the operation may be carried out by inverting the bolster 8 and resting it upon suitable supports 40, as shown in Figure 8, where it will be elevated from the floor. Then the springs 15 and 25 may be placed on the spring-engaging portions of the bolster. Then the spring seats 14 and 24 may be placed upon the springs. Then the blocks 41 may be placed upon the projections 14a and 24a of the spring seats and a beam 42 may be placed upon blocks 41. This beam may be moved downwardly to compress springs 15 and 25 by lowering a weight from an overhead crane or like tool, or by the ram of a hydraulic press, or a yoke comprising elements 43, 44 and 45 may be applied to the assembly, as shown in Figure 9, and a jack 46 used as indicated to force beam 42 downwardly, thus compressing springs 15 and 25. Then levers 10 and 20, with their pins 11, 21, 13 and 23, may be assembled with the bolster and a block 47 placed between lever 10 and the opposing rib
